ORA A. RAINWATER, OF MARYSVILLE, WASHINGTON, ASSIGNOR OF ONE-HALF TO
MRS. WILLIAM J. WHITE

DROPPING BOARD FOR USE IN POULTRY HOUSES

Application filed September 7, 1927. Serial No. 217,959.

This invention relates to dropping boards for use in poultry houses and more particularly to that class having a sanitary, movable surface to receive the droppings and from which they may be removed as the surface is moved into contact with some suitable agency as a brush or scraper.

Many attempts have been made to construct a practical, self-cleaning dropping board to relieve poultrymen of the most disagreeable drudgery connected with their business, but it has been found difficult to construct one of cheap material and at the same time simple and easy to operate.

The purpose of this improved dropping board is to provide one that is sanitary, that can be installed in any type of poultry house, one constructed of inexpensive material, easily repaired, and that requires but little power or strength to operate.

In accomplishing these objects, I have provided the improved details of construction, the preferred forms of which are illustrated in the accompanying drawings, wherein—

Figure 1 is a perspective view of the device, showing the construction and installation with sheet partly wound on roller and part of top sheet cut away.

Figure 2 is a perspective view of an alternative construction.

Figure 3 is a perspective view, partly cut away, of the roller winding assembly.

Figure 4 is a sectional view of the oiling tank.

Referring more in detail to the drawings—

The frame of the device, as an entirety, is designated by reference numeral 1, and it comprises the opposite end sections having uprights 2—2 and 3—3 connected across the top ends, respectively, by the cross bars 4 and 4'. These end sections are rigidly joined along opposite sides of the frame by the horizontal connecting beams 5—5' in which the opposite ends of a plurality of transversely disposed rollers 6 are rotatably mounted at spaced intervals longitudinally 50 of the frame and which serve to support the

flexible, dropping receiver 7, presently described.

The dropping receiver consists preferably of two sheets of oiled paper 8 and 9, disposed one on top of the other and secured at one end to a cross bar 7' and at their other ends secured to and adapted to be wound onto and from a drum 16 that is mounted revolubly on a cross shaft 14 extended between the end standards 3—2. 55 Also, revoluble on the shaft 14 adjacent to the end of the drum 16, is a relatively short drum 13, and, secured to this so that it may be moved thereon, is one end of a cable 11 which extends to the opposite end of the 60 frame below the rollers 6 and then passes over a pulley wheel 12 secured to the end of the frame and then back and is secured to the cross bar 7' at the end of the dropping receiver.

In this construction, the bottom sheet 9 serves as a support for the top sheet 8 and also provides a reserve oil supply as is hereinafter described. The opposite side edges of the sheet 9 are reinforced by binder tapes 75 10 of suitable material to preserve the edges and relieve the paper strip of the strain incident to winding.

For the purpose of rotating the shaft 14 to wind or unwind the strip 7 on the drum 16, I have equipped the shaft at one end with a crank 15, and fixed to the shaft 14 between the drums 13 and 16, is an arm 17 equipped at its outer end with oppositely directed pawls 18 and 19 which, respectively, co-operate with ratchet teeth 18' and 19' formed on the peripheries of the adjacent end flanges of the drums 13 and 16.

A scraper plate 20 is pivotally mounted between the uprights 2—2' and has a free 90 edge held yieldably in scraping contact with the surface of the dropping strip 7 as it winds about the drum 16, by means of a coiled spring 21 that is attached to the plate and to the frame piece 2.

Rotatably mounted between the uprights 2—2' above the strip 7 and drum 16 on a supporting shaft 23 that is extended between these uprights, is a cylindrical, horizontally disposed oil tank 22 provided with one or 100

more rows of small perforations 24. This tank has a top filling opening 25 over which a cap 25' is fitted and a spring plate latch 26 is attached to one end of the tank and this has a notch adapted to coact with studs 27-27' on the frame piece 2' to hold the tank against rotation, with the row of perforations upwardly or downwardly directed. A strip of felt 28, or other suitable material, is attached to the tank for the purpose of spreading the oil contents of the tank evenly when the tank is turned with the perforations downwardly to deliver the oil onto the dropping receiving strips.

15 Cross pieces 29 serving as roosts are supported by the cross bars 4-4' above the dropping receiver 7.

Assuming the device to be so constructed, its operation is as follows:

20 The dropping receiver 7, when in service, is extended the full length of the frame beneath the roosts. When it is desired that it be cleaned, the pawl 18 is disengaged from the drum 13 and pawl 19 engaged with its drum, then by turning the crank 15 the sheets 8 and 9 are wound onto drum 16, and as they are wound thereon, the scraper plate 20 scrapes the droppings therefrom and they may be caught in any suitable receptacle.

25 At the completion of this operation, the pawls 18 and 19 are reversed, thus freeing drum 16 and securing drum 13, to which cord 11 is attached to the shaft 14. The latch 26 of the tank 22 is released and the tank turned with openings downward. Then, by turning the handle 15 in the reverse direction, the cord 11 is wound on the drum 13 and the dropping board sheets are returned to the service position under the roosts. At

30 the same time oil pours from the tank 22 through the perforations 24 onto the surface of dropping board sheets and is spread evenly by the felt swab 28. At the conclusion of this operation, the tank 22 is rotated

35 until the perforations are upward above the level of the tank's contents and the tank secured in such position by dropping the latch 26 over the pin 27 attached to the upright 2'.

The principal feature of this invention consists of the double sheets of paper constituting the dropping receiver and the means for oiling of the sheets. Used automobile crank case oil mixed with a disinfectant such as creosote has been found best adapted to the purpose. Paper is used primarily because of its cheapness and also because of its oil absorbent qualities and the resultant smooth or glazed surface which facilitates the scraping off of the droppings.

40 The double sheet is used because the bottom sheet can be made of a heavier and cheaper quality of material, but principally because the oil held therein serves to reinforce the oil content of the top sheet. The water in the droppings often causes the oil in the top

sheet, or a single sheet, to rise to the top thus exposing the fabric to the chemical action of the droppings which results in adhesion of the droppings to the sheet and in a short time destroying it. By means of the oil in the bottom sheet reinforcing the top sheet through capillary attraction, this adhesion is prevented. Another advantage in the use of paper lies in the ease of making needed repairs when the sheets become worn or mutilated for any reason.

70 In Figure 2 is shown an alternative form of construction for use in small poultry houses, wherein a double belt like dropping board is used and wherein cords or tapes 75 constitute a part of the belt.

80 It is obvious that many of the details of construction may be varied without departing from the spirit of the invention and, for this reason, it is not desired that the claims 85 be limited only to the details shown.

Having thus described my invention what I claim as new therein and desire to secure by Letters-Patent, is:

1. A device of the character described 90 comprising a frame structure having opposite end sections, a plurality of supporting rollers in the frame, a horizontal shaft revolvably mounted in one of said end sections, a pulley on the other end section, a relatively 95 long and short drum revolvable on the shaft, means for rotating the shaft, an arm fixed to the shaft between the drums, oppositely directed pawls fixed to the arm for engaging the drums, respectively, to rotate them 100 with the shaft, a dropping board composed of a plurality of superimposed, flexible strips of paper, or the like, attached at one end to the larger drum, a cable attached to the other end of the board and extended 105 over said pulley and back to the short drum and adapted to be wound onto said drum to unwind the board from its drum, and to draw it out across said supporting rollers, a scraping plate mounted to engage the top 110 of the board as it is wound onto its drum, and a solution container mounted above the drums, having openings therein from which a solution may be discharged onto the board as it is drawn out.

115 2. A device as in claim 1, wherein means is provided for supporting the container in position to retain or discharge its contents.

120 Signed at Everett, Washington, this 22nd day of August, 1927.

125 ORA A. RAINWATER.
